United States Patent Office

Des. 176,372

Patented Dec. 13, 1955

176,372

LIPSTICK CONTAINER

Edward Noyack, Seymour, Conn., assignor to Revlon Products Corporation, New York, N. Y., a corporation of New York

Application January 27, 1955, Serial No. 34,252

Term of patent 7 years

(Cl. D86—10)

Fig. 1.

Fig. 2.

Fig. 1 is a view in elevation of a lipstick container, showing my new design.

Fig. 2 is a top end view, the opposite end being substantially similar thereto.

I claim:

The ornamental design for a lipstick container, as shown and described.
